(57) **CLAIM**

The ornamental design for a display screen with transitional graphical user interface, as shown and described.

DESCRIPTION

FIG. 1 is front view of a first image in a sequence of a display screen with transitional graphical user interface.

FIG. 2 is front view of a second image in a sequence of a display screen with transitional graphical user interface.

FIG. 3 is front view of a third image in a sequence of a display screen with transitional graphical user interface.

FIG. 4 is front view of a fourth image in a sequence of a display screen with transitional graphical user interface.

FIG. 5 is front view of a fifth image in a sequence of a display screen with transitional graphical user interface.

FIG. 6 is front view of a sixth image in a sequence of a display screen with transitional graphical user interface.

FIG. 7 is front view of a seventh image in a sequence of a display screen with transitional graphical user interface.

FIG. 8 is front view of an eighth image in a sequence of a display screen with transitional graphical user interface.

FIG. 9 is front view of a ninth image in a sequence of a display screen with transitional graphical user interface.

FIG. 10 is front view of a tenth image in a sequence of a display screen with transitional graphical user interface.

FIG. 11 is front view of an eleventh image in a sequence of a display screen with transitional graphical user interface.

FIG. 12 is front view of a twelfth image in a sequence of a display screen with transitional graphical user interface.

FIG. 13 is front view of a thirteenth image in a sequence of a display screen with transitional graphical user interface.

FIG. 14 is front view of a fourteenth image in a sequence of a display screen with transitional graphical user interface.

FIG. 15 is front view of a fifteenth image in a sequence of a display screen with transitional graphical user interface.

FIG. 16 is front view of a sixteenth image in a sequence of a display screen with transitional graphical user interface.

FIG. 17 is front view of a seventeenth image in a sequence of a display screen with transitional graphical user interface.

FIG. 18 is front view of an eighteenth image in a sequence of a display screen with transitional graphical user interface; and,

FIG. 19 is front view of a nineteenth image in a sequence of a display screen with transitional graphical user interface. The appearance of the transitional graphical user interface of the embodiment sequentially transitions between the images shown in FIGS. 1-19. The process or period in which one image transitions to another image forms no part of the claimed design.

The outermost broken line rectangle shows the display screen and forms no part of the claimed design.

The long dash, short dash and dotted line within the outermost broken line rectangle do not form a part of the claimed design.
